STILT TOY

William S. McIlvain, Austin, Tex.

Application September 1, 1959, Serial No. 57,405

Term of patent 14 years

(Cl. D7—7)

Fig. 1 is a side elevational view of a stilt toy showing my new design;

Fig. 2 is a front elevational view thereof;

Fig. 3 is a top plan view thereof; and

Fig. 4 is a bottom plan view of the same.

I claim:

The ornamental design for a stilt toy, as shown.
